UNITED STATES PATENT OFFICE.

JOHN A. MEEKER, OF POTSDAM, NEW YORK.

BUTTER-FAT GAGE.

1,375,057.

Specification of Letters Patent. Patented Apr. 19, 1921.

Application filed May 22, 1920. Serial No. 383,561.

To all whom it may concern:

Be it known that I, JOHN A. MEEKER, citizen of the United States, residing at Potsdam, in the county of St. Lawrence and State of New York, have invented certain new and useful Improvements in Butter-Fat Gages, of which the following is a specification.

My invention relates to new and useful improvements in a device for accurately reading the calibrated tube of a test bottle used in determining the percentage of butter fat in milk and cream.

One of the objects of my invention is to provide a device of the character specified which will be simple in mechanical construction and can be operated to obtain the desired reading with the fewest possible movements on the part of the operator.

With these general objects in view, the invention consists in certain novel and peculiar features of construction and combination of parts as hereinafter described and claimed; and in order that it may be fully understood reference is to be had to the accompanying drawings, in which similar reference characters indicate corresponding parts in all the views.

Figure 1 is a front elevation of my improved gage showing a test bottle in position for reading;

Fig. 2 is a side elevation of the same;

Fig. 3 is a sectional view on the line 3—3 looking in the direction of the arrow; and

Fig. 4 is a section on the line 4—4 looking in the direction of the arrow and showing the operating means for the pointers.

Referring to the drawing, 1 is a suitable support carrying parallel fixed guides 2. Reciprocatingly mounted on the said guides is a harness 3 which carries the lower pointer 4 fixedly secured thereto, and the upper pointer 5, which is mounted to reciprocate with respect to the said lower pointer. The main frame of the harness is shaped of metal to provide a plate member 6, a top angle portion 7, a bottom angle portion 8, tubular parallel guide sleeves 9, coöperating with the fixed guides 2, and angular ears 10.

A center guide 11 also fixedly carried by the reciprocating harness forms a suitable bearing surface for the reciprocating upper pointer 5, which latter is provided with a collar 12 secured thereto, to furnish an enlarged bearing surface.

Secured to the under side of the support

1, is a crank shaft 13 carrying a crank 14 and a hand wheel 15. A pitman 16 is pivotally connected to the crank and to the angle 8 of the harness 3.

Pivotally mounted in the ears 10 of the harness 3 is another crank shaft 17 provided with a hand wheel 18. A pitman 29 is pivotally connected to the crank shaft 17 and the upper pointer 5. For holding the said pitman in placed position, spring tension members 23 and 24 are provided and which are in frictional engagement with their respective crank shafts.

For holding the bottle securely in position 70 a socket 19 having a lateral entrance is mounted on the support 1 and is constructed of spring metal to provide the laterally movable spring end portions 19' to permit insertion and removal of the bottle. Secured 75 to the upper end of the guides 2 is a spring metal strap 20 provided at one side with a stopper 21 for entering the neck of the bottle.

The pointers 4 and 5 are curved as at 22 80 to fit against the neck of the bottle and only project part way across the neck so that the reading of the gage is not obscured as it would be if they projected across the whole way.

The operation of my invention is as follows: The layer of fat having separated out in the calibrated part of the neck of the bottle and it being desired to read the same, the bottle is held in a slightly tilted position while the stopper 21 is inserted therein and then the bottom of the bottle is slid into place between the spring members 19' of the socket 19. The hand wheel 15 is then rotated in a direction to move the harness 3 95 until the lower pointer is at the lower end of the layer of fat. The hand wheel 18 is then rotated to move the upper pointer relative to the lower pointer and to the position where the former is opposite the upper end 100 of the layer of fat. The hand wheel 15 is then rotated to move both pointers in fixed relationship so as to bring the lower pointer opposite zero on the scale; the upper pointer then indicates the reading to be made.

From the description as above set forth it is obvious that I have provided a device which possesses the following advantages: The bottle can be readily placed and removed from position with one hand and the instrument operated with the other. With the bottle in position, only three motions

will be necessary for a reading, namely, moving the lower pointer to position, moving the upper pointer to position, and then moving the lower pointer to zero position.

- 5 The pitman motion is desirable because in order to move the pointers to desired position only a small turning movement of the hand wheel is necessary as compared with the greater movement effected by screws.
- 10 While I have described my invention for use in reading the scale on a bottle for testing milk, it is obvious that it would be of application where a similar apparatus for analogous purposes might be used.
- 15 From the above description it will be apparent that I have produced a device of the character described, which possesses all the features enumerated as desirable, and while I have illustrated and described the preferred form of the invention, it will be understood that I reserve the right to all changes properly falling within the scope and spirit of the appended claims.
- 20 Therefore what I claim as new and desire to secure by Letters Patent is—

25 1. A gage comprising a support, a guide carried thereby, a member adapted to reciprocate on the said guide, a pointer carried

by the said member, a second pointer carried by the said member and adjustable with 30 relation to the first pointer, a crank shaft mounted on the support and a pitman connected to the said member and the crank shaft.

2. A gage comprising a support, a guide 35 carried thereby, a member adapted to reciprocate on the said guide, a pointer carried by the said member, a second pointer carried by the said member and adjustable with relation to the first pointer, means for adjusting the second pointer, comprising a crankshaft rotatably mounted on the said member and a pitman connected to the crank shaft and to the second pointer.

3. A gage comprising a support, a guide 45 carried thereby, a member provided with a pointer movably mounted on said guide, a test bottle supported in proximity to the said pointer, a stopper for engaging the neck of the bottle, a spring member for 50 supporting the stopper and means for supporting the spring member.

In testimony whereof I hereby affix my signature.

JOHN A. MEEKER.
